UNITED STATES PATENT OFFICE.

OTTO M. LONG AND ELMER H. MATKIN, OF BONNE TERRE, MISSOURI.

TOOL-SHARPENER.

1,112,461.

Specification of Letters Patent.

Patented Oct. 6, 1914.

Application filed May 28, 1912. Serial No. 770,812.

To all whom it may concern:

Be it known that we, OTTO M. LONG and ELMER H. MATKIN, citizens of the United States, residing in the city of Bonne Terre 5 and State of Missouri, have invented a new and useful Tool-Sharpener, of which the following is a specification.

This invention relates to tool sharpeners, and it consists of the novel construction, 10 combination and arrangement of parts hereinafter shown, described and claimed.

An object of the invention is to provide a sharpener adapted for use in cutting or sharpening tools of the hardest structure, 15 such, for instance, as devices composed of carborundum, emery or the like.

By reference to the illustration it will be understood that the invention is especially useful for shaping the disks of carborundum 20 or emery employed by dentists, and for similar purposes, but it will be also understood that we do not deprive ourselves of any of the uses in which the invention may be employed.

25 In the accompanying drawings in which we have illustrated a preferred embodiment of our invention, Figure 1 is an elevation showing the device in use for re-shaping a disk of the kind commonly employed by dentists. Fig. 2 is a side elevation also illustrating the device applied to the same use. Fig. 3 is an end view of the sharpener. Fig. 4 is a sectional view on the line 4—4 of Fig. 1.

35 The invention consists preferably of a support 1 of such a size that it may easily be held and retained in the hand, and which may be provided with grooves or serrations 2 to prevent slipping. An element 3 is supported by the support 1, having dove-tailed connection therewith and is capable of longitudinal movement thereon. The element 3 is formed with a longitudinal slot 4, and a removable stud 5 extends through the support 1 and into the slot 4, and constitutes an abutment to limit movement of the member 3 with respect to the supporting member 1. The member 3 may also be formed with notches or serrations 6 for engagement 45 by the thumb or finger, whereby said member may be firmly moved and retained in the desired position. The upper end of the member 3 is enlarged, as indicated at 7, and has firmly embedded therein a diamond cutter 8.

The upper end of the supporting mem-

ber 1 is formed with a suitable depression or notch 9 adapted to receive and retain the support of the device or instrument to be sharpened or re-shaped. In the drawing we have illustrated a disk 10 of the kind commonly employed by dentists. The disk, as usual, is attached to the shaft 11 driven by the engine in the usual and well understood manner. While the shaft 11 rests within the notch or depression 9 and is rapidly rotated, the element 3 is moved with respect to the supporting member 1 to bring the diamond cutter 8 into contact with the periphery of the rotating disk. Any irregularity on the periphery of the disk will be removed, and the disk will be re-shaped in the required circular form adapted for further or additional use, to which it could not have been put, however, while any material irregularities were in its periphery.

We are aware that the invention may be applied to other uses than that specifically illustrated and described, and that there may be variations and alterations in the construction and arrangement of the parts without departure from the spirit and scope of the invention. Therefore, we do not restrict ourselves to specific features or uses except as pointed out in the appended claims.

What we claim and desire to secure by Letters Patent of the United States is:

1. In a device of the character described, a support provided at one end with an implement rest, an element arranged to slide longitudinally against one side of said support and having a slot therein, a stud on said support extending through said slot and limiting movement of said element toward and away from said implement rest, manually engageable serrations on said element whereby said element may be firmly held in any desired position against the side of said support, and a cutter carried at the end of said element toward said implement rest, substantially as described.

2. In a device of the character described, a support provided at one end with an implement rest, a cutter carrier having a longitudinal slot and having tongue and groove connection with said support, manually engageable serrations on said cutter carrier whereby said carrier may be firmly held in any adjustment against the side of said support, a stud removably carried by said support and extending through said slot to limit movement of said cutter carrier toward and

- away from said implement rest, and a cutter mounted in the end of said cutter carrier which is toward said implement rest, substantially as described.
- 5 3. In a device of the character described, a support provided with an implement rest in one end thereof, a sliding element arranged to operate against one side of said support toward and away from said rest, a 10 tongue and groove connection at each side of said support holding said element in position, said element having a longitudinal slot between said tongue and groove connections, a projection on said support extending into 15 said slot and limiting movement of said element, manually engageable serrations on said element whereby said element may be firmly held in any adjustment, and a cutter on one end of said element adjacent said 20 implement rest, substantially as specified.
4. In a device of the character described, a support having an implement rest in one end thereof, a cutter carrier, tongue and groove connection between said cutter carrier and said support, a cutter in one end of 25 said carrier adjacent said implement rest, and a knurled thumb rest on said carrier permitting engagement thereof for positioning and holding said carrier in relative adjustment with said support, for the purpose 30 set forth.

In witness whereof, we have signed this specification in the presence of two subscribing witnesses.

OTTO M. LONG.
ELMER H. MATKIN.
